(57) CLAIM

The ornamental design for a jacket with snakeskin-like pattern, as shown and described.

DESCRIPTION

FIG. 1 illustrates a front view of a jacket with snakeskin-like pattern showing my new design;

FIG. 2 is a rear view thereof;

FIG. 3 is an enlarged view of the right breast pocket trim, the remainder of the jacket removed for ease of illustration;

FIG. 4 is an enlarged view of the left breast pocket trim, the remainder of the jacket removed for ease of illustration;

FIG. 5 is an enlarged view of the right waist pocket trim, the remainder of the jacket removed for ease of illustration; and,

FIG. 6 is an enlarged view of the left waist pocket trim, the remainder of the jacket removed for ease of illustration.

1 Claim, 6 Drawing Sheets---
